FLUID COMPRESSOR

Burton S. Aikman, Wilkinsburg, Pa., assignor to
The Westinghouse Air Brake Company, Wil-
merding, Pa., a corporation of Pennsylvania

Application March 27, 1936, Serial No. 71,227

7 Claims. (Cl. 230—211)

This invention relates to fluid compressors, particularly to air cooled compressors, and the principal object of the invention is to provide a simple and inexpensive arrangement for effectively cooling a compressor.

The above and other objects and advantages of the invention made apparent hereinafter are attained by an illustrative embodiment of the invention, subsequently to be described, and 10 shown in the accompanying drawing wherein,

Fig. 1 is a vertical sectional view of a compressor embodying my invention, and

Fig. 2 is a fragmentary view taken on the line 2—2 of Fig. 1, showing a detail of the fan construction.

As shown in Fig. 1, the compressor has a sectional casing comprising a crank case section 3, an end section 4, and a compression cylinder section 5. The crank case section 3 has a securing flange 6 at one end thereof, whereby the compressor casing is removably secured to the end face of the casing of a driving motor 7, as by bolts or screws 8. It will be noted that the usual end section of the motor casing containing 20 a bearing for supporting one end of the motor armature shaft 11 is not required, because a suitable bearing 9 for the motor shaft is provided in a recess 12 in the casing section 3.

The end of the motor shaft 11 extends into 25 the crank case chamber 13 and has secured thereto, as by a key 14, a tubular crank shaft 15 having an eccentric 16 and counterweight 17.

The end section 4 of the compressor casing is secured, as by bolts or screws 19, to the section 30 3 to close the end opening 21 in the section 3 opposite the end flange 6, the casing section 4 being provided with a suitable journal 22 for supporting the tubular crank shaft of the compressor.

40 The end of the compressor crank shaft 15 extends beyond the outer end of the journal 22 and a driving means, such as the pulley wheel 25, is secured thereto as by a key 24, for a purpose hereinafter made apparent.

45 The upper portion of the crank case section 3 is cylindrical in form and has a bore 26 in which the lower portion of the piston 27 of the compressor is guided. A connecting rod 28 of suitable construction, is provided for connecting the wrist pin 29, associated with the piston 27, and the eccentric 16 on the crank shaft 15, the lower end of the connecting rod 28 having a downwardly projecting splash finger or rod 31 50 adapted to pass through the fluid lubricant con-

tained in the lower portion of the crank case chamber 13.

The compression cylinder section 5 is provided with a flange which is suitably secured to a corresponding flange at the upper end of the crank case section 3, as by bolts or screws 33, and contains a bore 34 adapted to form a compression chamber 35 of the compressor, the diameter of the bore 34 being somewhat larger than that of the bore 26.

10 The piston 27 is provided with a suitably enlarged head portion for operating in the bore 34. A check valve device 37 mounted in the head portion is adapted to prevent flow of fluid under pressure from the compression chamber 35 to the crank case chamber 13 during the compression stroke of the piston and to permit flow of fluid under pressure from the crank case chamber into the compression chamber during the intake stroke of the piston. The check valve device 37 in the piston 27, it should be understood is not a part of my present invention, it being shown merely for the purpose of illustrating some means for providing a partial vacuum in the crank case chamber 13 whereby the possibility of leakage of oil from the crank case section 3 is minimized.

15 A plurality of intake ports 38 in the wall of the bore 34 are uncovered by the piston, when it is adjacent the lower extremity of its stroke, to admit air into the compression chamber 35. The crank case section 3 has suitable openings 39 in the flange thereof to open the ports 38 to the atmosphere.

20 Formed on the top of the casing section 5 and extending upwardly is a hollow internally threaded projection 41 within which the discharge valve 42 of the compressor is contained. A pipe-fitting 43 provided with external threads 44 at one end thereof is threaded into the projection 41 in sealed relation thereto and a coil spring 45, interposed between the inner end of the pipe-fitting 43 and the discharge valve 42, yieldingly urges the valve 42 into seated relation on an annular rib seat 46 surrounding the discharge port 47 leading out of the compression chamber 35. A discharge pipe 48 threaded into the upper or outer end of the pipe-fitting 43 serves to conduct the compressed air or fluid to a suitable receiver or other equipment not shown.

25 According to my invention, I further provide a cooling fan device which comprises a cylindrical shell 51 having an inner portion 52, of a diameter to closely surround the upper

flange portion of the crank case section 3 and the compression cylinder casing section 5, and an outer portion 53 of larger diameter, a plurality of radially extending fan blades 54 being secured at the outer ends thereof, as by welding, to the shell 51 within the portion 53, and at the inner ends thereof to a ring 55.

The shell 51 is rotatably supported in depending relation from a shoulder or flange 56 on the pipe-fitting 43, the inner ring 55 having a bearing member, such as the ball bearing 57, secured therewithin, as by a press fit.

The shell 51 may be connected to and rotatively driven by the compressor crank shaft in any suitable manner, as by means of a beveled clutch wheel or idler pulley 59 interposed between the lower beveled end of the shell 51 and a beveled face 61 on the pulley wheel 25 attached to the compressor crank shaft 15.

20 The beveled clutch wheel 59 is rotatably mounted, as on a pin 62 having threads on the end thereof for screwing the pin 62 into a tapped hole 63 at the upper end of the casing section 4. The clutch face of the wheel 59 is provided with 25 a suitable facing 60 of frictional material. A coil spring 65, interposed between the hub portion of the beveled wheel 59 and a flange or head 66 on the pin 62, yieldingly urges the beveled wheel 59 into frictional contact with the shell 51 and the pulley wheel 25, the tension of the spring 65 being adjustable by turning the pin 62. A bearing member, such as the ball bearing 68, serves to mount the hub of the beveled wheel 59 30 on the pin 62 and surrounds the pin 62 loosely enough to permit the beveled wheel 59 to be cocked from a position normal to the axis of the pin and thereby adjust itself to irregularities of 35 rotation of the shell 51 and of the wheel 25.

40 A baffle member or deflector 69, of conical shape, is suitably secured within the lower portion 52 of the shell 51, as by welding the lower wide end thereof to the shell 51, for the purpose of directing the cooling air flowing through the shell 51 against the outer surface of the casing section 5 and between successive vertical radially extending cooling fins 71 integrally formed on or secured to the casing section 5.

In operation, the motor 1 drives the crank shaft 15 of the compressor directly and the piston 50 27 of the compressor is accordingly reciprocated in the compression chamber bore 34. Air is drawn, by suction, into the compressor chamber 35 through the openings 39 in the casing section 3 and through the intake ports 38 in the casing section 5, and is discharged from the compressor chamber 35, on the upstroke of the piston, past the discharge valve 42 to the pipe 48.

55 Simultaneously, the shell 51 and the fan blades 54 are rotated, and cause flow of cooling air upwardly through the shell 51 completely encircling the upper cylindrical portion of the crank case section 3 and the compression cylinder casing section 5. The cooling air flowing upwardly through the interior of the shell 51 is directed forcibly against the outer surface of the compression cylinder casing section 5 and between successive fins 71 by the deflector member 69, the heated air being ultimately expelled out of shell 51 upwardly from the fan blades 54.

70 It will be understood that the upper open end of the shell 51 may be provided with a suitable screen for protection purposes.

75 The advantages of the particular arrangement, construction and operation of the cooling fan device which I have devised are that it is

simple and inexpensive to manufacture, rugged and dependable in service, and highly effective in cooling due to the concentration of the cooling air in close contact with and in encircling relation to the compression cylinder. 5

While but one embodiment of my invention has been described and shown, it will be understood that various omissions, additions or changes may be made therein without departing from the spirit of my invention and it is therefore not my intention to limit the scope of my invention except as necessitated by the prior art. 10

Having now described my invention, what I claim as new and desire to secure by Letters Patent is:

15 1. A fluid compressor comprising a cylinder having a chamber in which fluid is compressed, a tubular shell concentrically surrounding and rotatably mounted on the said cylinder, and fan blades secured to the interior of the tubular shell 20 adapted to cause flow of cooling air axially through said shell and past said cylinder in encircling relation thereto upon rotation of said shell.

25 2. A fluid compressor comprising a cylinder having a compression chamber, a piston operating in said cylinder for compressing fluid in the chamber, a crank shaft for operating the piston, a tubular shell concentrically surrounding and rotatably mounted on the said cylinder, fan 30 blades secured to the interior of the tubular shell adapted to cause flow of cooling air axially through said shell and past said cylinder in encircling relation thereto upon rotation of said shell, and means connecting the crank shaft and 35 shell for rotating said shell upon rotation of the crank shaft.

40 3. A fluid compressor comprising a cylinder having a chamber in which fluid is compressed, a tubular shell concentrically surrounding the 45 said cylinder, radially extending fan blades secured at the outer ends thereof to the interior of said shell and rotatably supported at the inner ends thereof on said cylinder, and means for rotating said shell and blades to cause flow of cooling air axially through the shell and past the 45 said cylinder in encircling relation thereto.

45 4. A fluid compressor comprising a cylinder having a chamber in which fluid is compressed, a hollow extension at one end of said cylinder 50 providing a passage through which fluid compressed in the chamber is discharged therefrom, a tubular shell concentrically surrounding said cylinder, radially extending fan blades secured at the outer ends thereof to the interior of said 55 shell and supported at the inner ends thereof on the said extension for rotation about the axis of the extension, and means for rotating said shell and fan blades to cause flow of cooling air axially through said shell and past said cylinder in encircling relation thereto.

60 5. A fluid compressor comprising a cylinder having a chamber in which fluid is compressed, a tubular shell concentrically surrounding and rotatably mounted on the said cylinder, fan blades 65 secured to the interior of the tubular shell adapted to cause flow of cooling air axially through said shell and past said cylinder in encircling relation thereto upon rotation of said shell, and a deflector secured to the interior of said shell for 70 directing the cooling air flowing through the shell into close contact with the said cylinder.

6. A fluid compressor comprising a casing having a cylinder forming a compression chamber, a piston operative in the chamber to compress 75

- fluid, a crank case chamber in said casing, a crank shaft within the said crank case chamber for reciprocating the piston, said crank shaft extending at one end out of said casing, a tubular shell concentrically surrounding the said cylinder and rotatably mounted thereon, said shell having an annular friction surface thereon, fan blades secured to the interior of said shell adapted to cause flow of cooling air axially through the shell and past said cylinder in encircling relation thereto upon 10 rotation of said shell, and means providing a driving connection between the exterior end of said crank shaft and said shell for effecting rotation of the shell upon rotation of the crank shaft.
- 15 7. A fluid compressor comprising a casing having a cylinder forming a compression chamber, a piston operative in the chamber to compress fluid, a crank case chamber in said casing, a crank shaft within the said crank case chamber for reciprocating the piston, said crank shaft extending at one end out of said casing, a tubular shell concentrically surrounding the said cylinder and rotatably mounted thereon, fan blades secured to the interior of said shell adapted to cause flow of cooling air axially through the shell and past said cylinder in encircling relation thereto upon 10 rotation of said shell, and means providing a driving connection between the exterior end of said crank shaft and said shell for effecting rotation of the shell upon rotation of the crank shaft.
- 15 7. A fluid compressor comprising a casing having a cylinder forming a compression chamber, a piston operative in the chamber to compress fluid, a crank case chamber in said casing, a crank shaft

within the said crank case chamber for reciprocating the piston, said crank shaft extending at one end out of said casing, a tubular shell concentrically surrounding the said cylinder and rotatably mounted thereon, said shell having an 5 annular friction surface thereon, fan blades secured to the interior of said shell adapted to cause flow of cooling air axially through the shell and past said cylinder in encircling relation thereto upon rotation of said shell, a wheel 10 secured to the exterior end of the crank shaft and having a peripheral friction surface thereon, and an idler wheel frictionally engaging the annular friction surface on the shell and the friction surface on the said wheel at the end of 15 the crank shaft for providing a driving connection between the crank shaft and the shell.
